[57] CLAIM

The ornamental design of a culinary finger guard, as shown and described.

DESCRIPTION

FIG. 1 is a perspective view of a first embodiment of the culinary finger guard with the user's hand shown in broken lines and forms no part of the claimed design.

FIG. 2 is a perspective view of the culinary finger guard of FIG. 1.

FIG. 3 is a left side elevational view of the culinary finger guard of FIG. 1; the right side elevational view being a mirror image.

FIG. 4 is a front elevational view of the culinary finger guard of FIG. 1.

FIG. 5 is a rear elevational view of the culinary finger guard of FIG. 1.

FIG. 6 is a top plan view of the culinary finger guard of FIG. 1.

FIG. 7 is a bottom plan view of the culinary finger guard of FIG. 1.

FIG. 8 is a perspective view of a second embodiment of the culinary finger guard.

FIG. 9 is a left side elevational view of the culinary finger guard of FIG. 8; the right side elevational view being a mirror image.

FIG. 10 is a front elevational view of the culinary finger guard of FIG. 8.

FIG. 11 is a rear elevational view of the culinary finger guard of FIG. 8.

FIG. 12 is a top plan view of the culinary finger guard of FIG. 8; and,

FIG. 13 is a bottom plan view of the culinary finger guard of FIG. 8.
